(57) **CLAIM**

The ornamental design for dual screen laptop, as shown and described.

DESCRIPTION

FIG. 1 is a perspective view of a dual screen laptop.

FIG. 2 is a right side view of the laptop of FIG. 1.

FIG. 3 is a left side view of the laptop of FIG. 1; and, FIG. 4 is a top view of the laptop of FIG. 1.

The features shown in dashed lines form no part of the claimed design.

The rear and bottom views of the article are not shown in the drawing or described in the specification. It is understood that the appearance of any part of the article not shown in the drawing or described in the specification forms no part of the claimed design. Therefore, the determination of patentability is based on the design for the article shown and described.
